UNITED STATES PATENT OFFICE.

JOHN SINKO AND DANIEL SZANTAY, OF CHICAGO, ILLINOIS, ASSIGNEES TO SINKO
TOOL & MFG. CO., OF CHICAGO, ILLINOIS, A CORPORATION OF ILLINOIS.

METALLIC BANK.

Application filed January 2, 1925. Serial No. 21.

This invention relates to metallic containers and banks and to the process for making the same. It has for one object to provide a bank which is made essentially of a single piece of metal and which is therefore strong and durable. It has for another object to provide a process for making the bank from a single piece of metal whereby it may be economically and rapidly made. Other objects will appear from time to time throughout the specification and claims.

My invention is illustrated more or less diagrammatically in the accompanying drawing, wherein:

Figure 1 is a partial plan view of a disc of metal from which the container is made;

Figure 2 is a vertical cross section through the container after it has been partially formed;

Figure 3 is a view similar to Figure 2 after the container has been further shaped;

Figure 4 represents a still further step;

Figure 5 shows the metallic shell of the bank after it has been completely formed and shows also an added ring which is inserted;

Figure 6 is a vertical cross section showing the ring inserted and fastened in place.

In this form the complete container or bank appears.

As appears in the drawings of Figure 1 the bank itself is made entirely from a single piece of metal. The form illustrated here-
35 with it shaped like a barrel. Barrel hoops are rolled into the bank casing and the bank casing proper is complete in the form shown in Figure 5. For the purpose of attaching a lid, however, a ring is set in. The ring
40 is fastened to the bank shell and the lid may then be put in place in engagement with the ring.

The process of forming the bank includes the following steps. A disc of metal is first
45 formed as shown in Figure 1. This is then stamped into a more or less cup-like form. The initial stamping may carry the forming as far as that shown in Figure 2 or it may not carry it so far, and more than one operation may be required to bring the disc into the form shown in Figure 2.

After being formed into a cup as shown in Figure 2, the container is swelled at the sides into the general barrel-like form shown in
55 Figure 3. In the next step the barrel hoops

are formed in the container, preferably being rolled into it and takes the form shown in Figure 4.

In the next step the upper edge of the barrel is trimmed and turned outwardly. 60 This is shown in the lower half of Figure 5.

By another process which forms no part of the present invention a ring which is shown in Figure 5 is formed; and in the 65 final process the ring is set into the barrel and its downwardly depending flange is turned and rolled outwardly to conform to the interior of the barrel. This ring is permanently and firmly engaged in the barrel 70 and forms a top engagement for a final closure.

Although I have shown an operative device, still it will be obvious that many changes might be made in size, shape and 75 arrangement of parts without departing materially from the spirit of my invention; and I wish, therefore, that my showing be taken as in a sense diagrammatic.

I claim:

1. The process of forming a metallic container from a single piece of metal which includes preparing a metallic sheet, cupping said sheet, bulging the sides of said cup outward, flaring outwardly the outer open edge of the cup, pressing within said cup a ring having a downwardly depending flange, and forming said flange to conform to the shape of the interior of said container.

2. The process of forming a metallic container from a single piece of metal which includes preparing a metallic sheet, cupping said sheet, bulging the sides of said cup outward, forming outwardly extending ribs about said cup, flaring outwardly the outer open edge of the cup, pressing within said cup a ring having a downwardly depending flange, and forming said flange to conform to the shape of the interior of said container. 90

3. The process of forming a metallic container from a single flat piece of metal which includes preparing a metallic sheet, cupping said sheet, bulging the sides of said cup outward, flaring outwardly the outer open edge of the cup, pressing within said cup a ring having a downwardly depending flange, and forming said flange to conform to the shape of the interior of said container. 100

4. The process of forming a metallic container from a single piece of metal which 110

- includes preparing a flat metallic disc, cupping said disc, bulging the sides of said cup outward, forming outwardly extending ribs about said cup, trimming and flaring outwardly the upper edge of said cup, pressing within said cup a ring having a downwardly depending flange, and spreading and forming said flange to conform to the shape of the interior of said container.
5. The process of forming a metallic container from a single piece of metal which includes preparing a flat metallic disc, cupping said disc, bulging the sides of said cup outward, forming outwardly extending ribs about said cup, one of them adjacent the open top, trimming and flaring outwardly the upper edge of said cup, pressing within said cup a ring having a downwardly depending flange, and spreading and forming said flange to conform to the shape of the interior of said container.
10. 6. The process of forming a metallic container from a single piece of metal which includes preparing a flat metallic disc, cupping said disc, bulging the sides of said cup outward, forming outwardly extending ribs about said cup, trimming and flaring outwardly the upper edge of said cup, pressing within said cup a ring having a downwardly depending flange, and pressing and forming
- said flange into the rib adjacent the upper edge and causing the flange to conform to the interior of said container.
7. As a new article of manufacture a metallic container formed of a single sheet of metal having outwardly bulged sides and an open top, an annular groove adjacent said open top, in combination with a ring formed with a downwardly depending skirt and an inwardly extending flange, said ring being seated in the open top and the inwardly depending skirt being forced into the groove.
8. As a new article of manufacture a metallic container formed of a single sheet of metal having outwardly bulged sides and an open top, an annular groove adjacent said open top, in combination with a ring formed with a downwardly depending skirt and an inwardly extending flange, said ring being seated in the open top and the inwardly depending skirt being forced into the groove, said receptacle having an inwardly depressed bottom and outwardly pressed beads at separated points throughout its height.

Signed at Chicago, county of Cook, and State of Illinois, this 19th day of December, 1924.

JOHN SINKO.
DANIEL SZANTAY.
